WATER-INSOLUBLE METAL SOAP AND
METHOD OF MAKING THE SAMEFrederick A. Stresen-Reuter and Charles Rimpila,
Chicago, Ill., assignors to Fred'k A. Stresen-
Reuter, Inc., a corporation of IllinoisNo Drawing. Application February 26, 1938,
Serial No. 192,882

8 Claims. (CL 37-16)

This invention relates to soap and soap manufacture and more particularly to water-insoluble metal soaps and to methods of making the same.

This application is related to my copending application Serial No. 192,884, filed February 26, 1938.

In accordance with our invention we have found that novel water-insoluble soaps can be formed from an organic acid-containing liquor obtained from wood as a by-product in the manufacture of paper such as that sold in the trade under the trade-mark "Spefa" and a heavy metal selected from the first, second and eighth groups of the periodic table consisting of copper, zinc and iron. This liquor is characterized by the presence of a major proportion by weight of unsaturated fatty acids calculated as oleic, linoleic and linolenic, a minor proportion by weight of rosin acids or acids calculated as rosin acids and a relatively small proportion of unsaponifiable (mainly sterols). A suitable liquor called "Spefa" employed in accordance with our invention has a specific gravity (at 15.5° C.) of about 969; an acid number of about 164.0; a saponification number of about 173.0; an ester number of about 9.4; an iodine number (Wijs) of about 148.0; and a thiocyanogen-iodine number of about 91.0, and is a refined mixture of fatty acids, rosin acids and sterols derived from the liquor from the sulfate-process treatment of woods such as pine.

A typical analysis of this liquor is as follows. In the following analysis and in all examples hereinafter set forth, the term "parts" indicates parts by weight.

Parts (approximate)	
Fatty acid calculated as linolenic acid	19.25
Fatty acid calculated as linoleic acid	10.50
Fatty acid calculated as oleic acid	23.04
Rosin acids (or acids calculated as rosin acids)	39.20
Unsaponifiables, largely sterols	8.01

In preparing the copper, zinc or iron soaps from the liquor used in accordance with our invention, the liquor may be first boiled in a suitable vessel with any suitable alkaline solution such as, for example, with aqueous caustic soda or potash, or with an organic amine compound such as triethanolamine, to form a water-soluble soap solution. The soap solution so formed may then be diluted suitably to about 20% solids in the case of sodium or potassium soaps, and to about 0% solids in the case of the triethanolamine

soap and the solution maintained at about 200° F. while the required amount of the metal compound is added. The metal soap is then formed by double decomposition and precipitates to the bottom of the vessel. The precipitated water-insoluble soap is then separated in any desirable manner, washed with boiling water and then slowly heated to about 350° F. to remove substantially all of the water therefrom.

The zinc and iron soaps embodying our invention may also be prepared by directly fusing the liquor with zinc and/or iron compounds such as the zinc and/or iron oxides or hydroxides. Thus, in accordance with our invention, the liquor may be heated to about 350° to 400° F. and the oxide or hydrate of the desired metal or mixture of metals slowly added. The mixture is held at about 400° F. or higher until the reaction is complete, as indicated by the formation of a clear pill when a small amount of the reaction product is dropped onto a glass slide.

In general, equivalent or stoichiometrical or other desirable amounts of the reactants are employed to produce the water-insoluble metal soaps embodying our invention. In carrying out the processes embodying our invention we have produced the water-insoluble copper, zinc and iron soaps and the mixed metal soaps such as copper and iron soaps, copper and zinc soaps, etc.

The following examples illustrate the methods employed in accordance with our invention to produce our novel water-insoluble copper, zinc and iron soaps.

DOUBLE DECOMPOSITION METHODS

EXAMPLE 1

35

Part I

100 parts of the liquor "Spefa" are mixed with 100 parts of water and 12.38 parts of sodium hydroxide in a suitable vessel. The mixture is boiled until the resulting water-soluble soap solution has a pH of about 8 to 9; the time of reaction being about three hours. The soap solution so formed is now diluted, suitably to about 20% solids content.

Part II

The water-soluble soap solution produced in accordance with Part I is then mixed with 25.39 parts of zinc sulphate in aqueous solution (about 20% solids) at about 200° F. The water-insoluble zinc soap is formed by double decomposition and precipitates to the bottom of the vessel. The precipitated zinc soap is washed several times

55

with boiling water as by stirring and decanting to remove any impurities therefrom and is then slowly heated to about 350° F. to form a dehydrated water-insoluble zinc soap.

5

EXAMPLE 2

A water-soluble soap is formed as in Part I of Example 1 and is treated with about 25.5 parts of ferric chloride in aqueous solution (about 20% solids) to form the water-insoluble iron soap. The soap is then washed and dried all as fully described in Part II of Example 1.

FUSION METHOD

15

EXAMPLE 3

100 parts of the liquor "Spefa" are heated in a suitable vessel to about 350° to 400° F. and about 12.55 parts of zinc oxide are then slowly added. The mixture is held at about 400° F. or higher until all of the zinc oxide has reacted with the liquor, as indicated by the formation of a clear pill on a glass slide.

The water-insoluble metal soaps embodying our invention may have an unusually high metal content which may closely approximate theoretical. Using the wood fatty acids such as the liquor "Spefa" in accordance with our invention, it is possible to obtain by the fusion method a zinc or iron soap having a higher metal content than is capable of being obtained by fusing zinc or iron compounds with rosin acids or with linseed and like fatty acids.

The water-insoluble metal soaps embodying our invention are readily soluble in suitable vehicles or solvents such as, for example, the light petroleum distillates including heavy naphtha, kerosene, kerosene, V. M. and P. naphtha, and the petroleum naphtha thinner sold in the trade under the trade-mark "Apcos"; paraffin oils, and the like; or in raw or bodied vegetable drying or semi-drying oils such as, for example, linseed, perilla, China-wood oil, soy bean, citicica, and the like; and in animal oils such as fish oils and the like. The solutions formed are homogeneous and relatively stable, and the water-insoluble soap will not, in general, readily settle out from the vehicle even when the solution is cooled to below room temperature. The water-insoluble soaps embodying our invention are more stable in solution than the corresponding soap of linseed, oleic or like fatty acids as in the prior art. The water-insoluble soaps embodying our invention will not oxidize when in solution.

In general, the water-insoluble soaps embodying our invention are relatively odorless and are especially adapted for use in varnishes, paints, printing inks, and the like. The zinc soaps produced in accordance with our invention have special utility in paints to prevent wrinkling of the coating. The iron soap is an excellent drier especially in baking blacks, varnishes and enamels. It has better drying characteristics than any of the known iron soaps containing an equivalent amount of metal. The copper soaps have fungicidal properties, and being readily soluble in petroleum thinners, are especially suitable for use in paints for coating ship bottoms.

In accordance with our invention we have also produced excellent water-insoluble soaps by reacting compounds of the above metals with the liquor "Spefa" which has been freed from all unsaponifiable materials as, for example, by washing the water-soluble soap of "Spefa" with petroleum ether. We have prepared also excellent water-insoluble soaps by the aid of syn-

thetic preparations of acids, either with or without saponifiables such as sterol or sterol compounds, which closely approximate the acids, in character and in amount, present in the liquor "Spefa". Thus, we have obtained satisfactory soaps by reacting, in the manner described above, compounds of the above metals with a mixture of acids, the major proportion of which is unsaturated fatty acids and the minor proportion of which is rosin or rosin acids and the like. The synthetic acid mixture used in accordance with our invention may, if desired, contain a small proportion of sterol and/or sterol compounds or like unsaponifiable materials.

5

Wood organic acid mixtures similar to "Spefa" such as "Indusoil", "Liqro" may be used in lieu of the "Spefa" in accordance with our invention.

We claim:

1. As a new reaction product, a water-insoluble copper soap of a product derived from pine wood comprising a major proportion of unsaturated acids, a minor proportion of rosin acids and a small proportion of an unsaponifiable material calculated as a sterol.

2. As a new reaction product, a water-insoluble zinc soap of a product derived from pine wood comprising a major proportion of unsaturated acids, a minor proportion of rosin acids and a small proportion of an unsaponifiable material calculated as a sterol.

3. As a new reaction product, a water-insoluble iron soap of a product derived from pine wood comprising a major proportion of unsaturated acids, a minor proportion of rosin acids and a small proportion of an unsaponifiable material calculated as a sterol.

4. The method of forming a water-insoluble soap comprising reacting a product derived from pine wood comprising a major proportion of unsaturated acids, a minor proportion of rosin acids and a small proportion of an unsaponifiable material calculated as a sterol with zinc oxide at a relatively high temperature.

5. The method of forming a water-insoluble soap comprising reacting a product derived from pine wood comprising a major proportion of unsaturated acids, a minor proportion of rosin acids and a small proportion of an unsaponifiable material calculated as a sterol with zinc oxide at a temperature in the order of about 350° to 400° F.

6. A water-insoluble soap comprising the reaction product of a compound of a metal selected from the class consisting of copper, zinc and iron and a mixture comprising a major proportion of unsaturated fatty acids, a minor proportion of rosin acids and a small proportion of a non-saponifiable material calculated as a sterol.

7. A water-insoluble soap comprising the reaction product of a compound of a metal selected from the class consisting of copper, zinc and iron and an organic acid mixture derived from wood comprising a major proportion of unsaturated fatty acids a minor proportion of rosin acids and a small proportion of non-saponifiable material calculated as a sterol.

8. A water-insoluble soap comprising the reaction product of a compound of a metal selected from the class consisting of copper, zinc and iron and an organic acid mixture derived from pine wood comprising a major proportion of unsaturated fatty acids, a minor proportion of rosin acids and a small proportion of sterols.

FREDERICK A. STRESEN-REUTER.
CHARLES RIMPILA.
